(57) **CLAIM**

The ornamental design for a desk, as shown and described.

DESCRIPTION

My new design for a desk, in one form has an X-shaped frame that can be made of wood or wood veneer that can be in a mocha and/or black and/or mahogany finish having a like-colored or brushed or polished chrome or brushed or polished nickel fastener heads. The upper frame for the desk can be a brushed nickel frame for a top working surface which can be glass.

FIG. 1 is a perspective view of a design for a desk showing my new design;

FIG. 2 is a top plan view thereof;

FIG. 3 is a front elevational view thereof;

FIG. 4 is a right side elevational view thereof;

FIG. 5 is a left side elevational view thereof; and,

FIG. 6 is a rear elevational view thereof.

The dashed lines indicate the cross members that can be used to provide structural support for the desk of the present invention; namely of those portions of the desk which do not form a part of the design.
